UNITED STATES PATENT OFFICE

ALLAN WALTER LEWIS, OF VANCOUVER, BRITISH COLUMBIA, CANADA, ASSIGNOR TO LEWIS OCEAN LOG RAFTING CO., OF PORTLAND, OREGON, A CORPORATION OF OREGON

LOG CARRIER

Application filed June 2, 1928. Serial No. 282,338.

My present application relates to my United States Patent Number 1,575,070 patented March 2, 1926, upon a log carrier.

The primary purpose and object of my invention is for use in the transporting of logs in marine traffic from the point of origin of the logs to the point of use of the same, either in inland waterways, or in the open sea.

Heretofore it has been the general custom in the transporting of logs to make the same up into surface rafts where the same are to be transported in relatively calm waters and to make the same into cigar shaped rafts where the same are to be towed over relatively long distances and especially in the open sea. Where logs are to be transported in the open sea, rips are encountered and the rafts are made up in cradles to form an assembled raft in the shape of an immense cigar. The log cradles being secured together by chains running entirely around the assembled structure which are then secured together. These rafts in western America sometimes attain a length of a thousand feet or more and great expense of both labor and money are required in the assembling and the disassembling of the rafts. Even when great care is exercised, they are sometimes wrecked by the heavy seas and the rafts become a total loss to the owners, or a liability to the companies transporting the same.

In my new and improved log carrier, I employ a scow-like structure having water-tight compartments disposed at the oppositely disposed ends of the structure and having a hold disposed therebetween into which full tree length logs may be placed and lashed for marine transportation.

One of the objects of my invention consists in lessening the elements of time and cost in the placing of the logs within the scow and the removability of the same therefrom when the point of destination is reached.

A further object of my invention resides in the limiting of the loss of logs in transportation thereof over relatively long distances by water transportation.

And still further objects of my invention consist in providing a log carrier that will require a minimum of towing energy con-

sistent with tremendous weights of cargo involved.

And still further objects of my invention reside in a hull, the central hold of which may be wholly or partially submerged to facilitate the loading of logs and which may be sufficiently submerged to permit the floating of the cargo from the hold. 55

A still further object of my invention resides in means for the application of towing connections that makes possible the safe and expeditious handling of the loaded scow in rough water. 60

And still further objects of my invention consist in providing simple and efficient 65 means for the flooding and emptying of the cargo hold and for the tilting of the scow at desired angle at either the port or starboard side to facilitate loading and unloading operations. 70

And still further objects of my invention reside in the simplified hull construction that may be used over relatively long operating periods with a minimum of repair and maintenance costs. 75

With these and incidental objects in view, the invention consists in certain novel features of construction and combination of parts, the essential elements of which are set forth in the appended claims, and a preferred form of embodiment of which is hereinafter shown in reference to the drawings which accompany and form a part of these specifications. 80

In the drawings:

Fig. 1 is a top, plan view, of my new and improved device shown during the loading of a relatively long tree length log. 85

Fig. 2 is a longitudinal, sectional view, taken on line 2—2 of Fig. 1, looking in the direction indicated. 90

Fig. 3 is a cross section view, taken on line 3—3 of Fig. 2, looking in the direction indicated. 95

Fig. 4 is a sectional view of a completely loaded scow, illustrating the fastening elements used in the lashing of the log cargo in place and position. 100

Fig. 5 is a sectional view of the scow, illustrating the same in submerged position to

facilitate the floating of the log cargo from the scow when the same has been partially submerged.

Fig. 6 is a sectional view taken on line 4—4⁵ of Fig. 2 looking in the direction indicated, illustrating the scow in list to facilitate the loading and unloading of the log cargo from one side of the log carrier, this being accomplished through the flooding of the water tight compartments on one side of the scow and at oppositely disposed ends to cause the listing of the scow for loading and unloading purposes.

Fig. 7 is a fragmentary, sectional view, taken on line 7—7¹⁵ of Fig. 2, looking in the direction indicated, the same being made to illustrate the pumping unit, the piping connections therefor, and the sea cocks for flooding the cargo holds and the water tight compartments.

Fig. 8 is a perspective view of the A frame structure from which the elevated line is supported.

Fig. 9 is a perspective view of the side strakes, or planking, and the stanchions to which the same are secured.

Fig. 10 is a perspective view of the oppositely disposed side of the mechanism illustrated in Fig. 9, but on a smaller scale.

Like reference characters refer to like parts throughout the several views.

I preferably form the hull of my log carrier of spaced side walls 1 and 2, and bottom planking 3. The side and bottom planking forms the skin of the carrier which is preferably made of wood. The carrier may be made of metal thus forming a flat bottomed carrier formed of a relatively watertight outer covering of wood strakes and bottom planks caulked and otherwise made watertight and of sufficient thickness to form a stiff and sea worthy hull. Stanchions 4 and 5 are disposed upon the inner skin surface to afford rigidity to the same and having a plurality of knees 6 and 7 disposed adjacent the stanchions. The knees are secured to the cross girders 8 running athwart the structure, and also affixed to the stanchions to stiffen the hull and make the same seaworthy.

I have found best results obtain where these knees are made of wood but I do not wish to be limited to wood knees, as metal knees may be used. A center keelson 9, runs longitudinally of the structure and one or more may be used, depending upon the width of the carrier and the length. The center keelson where wooden knees are used would preferably be fabricated out of wooden members secured together by metallic fastenings of sufficient width and size to properly stiffen the carrier for the service to which the same is intended but where metallic knees are used, I have found the center keelson gives better results and a longer life where the same is made of reinforced concrete. The reinforced

concrete also being of a greater specific gravity substantially lowers the center of gravity of the carrier and makes the same have a greater seaworthiness. Where an all wood carrier hull is made, the same may require ballast on the bottom of the hold to facilitate the submerging of the hull to or below the gunwale lines of the central hold. The A frame posts 10 and 11 are disposed at either end of the hold secured together at their upper meeting ends as at 12 in Fig. 8, which may be secured together by any suitable fastening means, as by strap iron shackles 13 and 14. Disposed adjacent the end surface of the meeting A frame posts and suspended therefrom is a shackle block 15 over which an elevated line 16 passes. The elevated line 16 runs the full length of the carrier, has a turn-buckle element 17, disposed therein terminating in a metallic eye-bar strap and shackle pins extending downwardly along the end of the carrier to strengthen and stiffen the same. The turn-buckle is preferably made of substantial length to compensate for the stretch of the line and the maintaining of the same in a relatively tight and working condition.

A traveling carriage 18 is disposed and rides upon the line 16 and is adapted to move and travel there along through the application of power through the haul back lines 19 and 20, the same being secured to drums of the winch 21 for reciprocating the carriage in desired placement along the elevated line 16. Depending from the carriage 18 are hooks 22 and 23 terminating the free ends of the lines 24 and 25 also running to drums upon the winch 21; so that either of the lines may be independently moved through the operation of the drums of the engine. In actual practice in the loading of my carrier, the hull is partially submerged by the opening of the sea cocks until the gunwales are slightly above the normal water level both inside and outside of the carrier. The log 26 to be loaded, as illustrated in Fig. 3 is floated alongside of the carrier and the lines are then passed beneath the log, as illustrated at 27 and 28 in Fig. 1 and the hooks are then made secure to the chains 29 and as tension is applied to the lines 27 and 28, the log is simultaneously rolled and lifted over the gunwale into the hold of the carrier. Water being disposed within the carrier, the logs are floated through the use of pike poles or other means to the opposite side of the carrier from which the same were rolled until a tier of full length logs are disposed within the carrier at the same time displacing a part of the water therein. A second tier of logs is then loaded into the carrier with the butts of the logs disposed in the oppositely disposed end of the hold, so that one layer of logs is loaded with the butts of the logs in one direction and the next layer of logs is

loaded with the butts in the opposite direction until the logs assume the position substantially that illustrated in Fig. 4, at which time the hold down fastenings 29 as illustrated in Fig. 4 are secured, at opposite ends to the fastening elements, thus maintaining the log cargo in a seaworthy condition; in which position the same are carried to their final destination. In order to protect the skin of the carrier and the gunwales from the abuse that they would be subjected to when logs of large diameter and great length are loaded by power means, I have found satisfactory results obtain where a structural element, as a channel iron is used having an outer leg 30 of substantial length disposed upon the outer upper strakes of the side walls crossing over the gunwale, as illustrated at 31 in Fig. 9, and downwardly extending on the inner surface and secured to the stanchion 32, thus forming a U shaped element having spaced side walls or legs 30 and 33 and having cross connecting element 31 with the legs of the channel downwardly extending therefrom. The outer leg which the log engages and over which the log is rolled, thus forms a fastening and protecting element of great strength. These elements increase the rigidity of the carrier and prevent the undue chafing and wearing of the logs as they are rolled into the hold of the carrier and therefrom outward as the logs are rolled from the carrier by the same being floated therefrom, as the hull is partially submerged. The carriage 18 is placed in the desired position for the handling of logs of any length to be loaded within the hold of the carrier. The oppositely disposed ends of the hull outwardly extending from the log carrying hold, are formed into a plurality of relatively watertight compartments, both in vertical and horizontal spaced relationship.

Referring to Fig. 7, I form the compartments between the bulk head 35, the outer skin 36, and the bridge deck 40. I then divide each of these main compartments which are on each end of the scow into a plurality of upper and lower compartments. This is done by placing a tween deck 34 in the middle of each compartment in a horizontal plane. These upper and lower compartments are then split into smaller compartments by a division wall 34A placed in a vertical plane therebetween. In this way is formed a plurality of main compartments 37, 38, 39, and 39A which are in turn divided into smaller secondary compartments as aforementioned and outlined. The purpose of such construction is to permit easy maneuvering of the craft and the cargo when it is being unloaded, and loaded. There is then all told, eight compartments, four on each end of the craft. Each is capable of being flooded independent of the other. A power driven pumping unit 41 as a centrifugal pump, is disposed in the

forward end of the carrier which is adapted to being driven by power means, as a driving shaft 42 from the engine of the winch 21. The pumping element 41 is secured to a sea chest 42 and the sea cocks 43 and pipe 44, which when open permit the inflow of water into the interior of the carrier and the closing of the valves 45, 46, 47 and 48 will automatically predetermine which of the holds of the carrier are to be flooded. When the sea cocks 43 and pipe 44 are closed after the compartments have been flooded, the pumping out of the spaces may be accomplished by the operation of the pumping element 41. The watertight compartments disposed between the bridge deck 40 and the tween deck 34 when flooded, permit of a greater submergence of the carrier than if only the lower compartments were flooded and the flooding of the compartments on the starboard side of either end will cause a list of the carrier to starboard, whereas the flooding of the compartments on the port side, only, will cause a listing of the carrier to port. The pumping of all of the compartments and the open hold may be simultaneously accomplished by the opening of the connections leading to the chest 42 to which the pump is attached directly or the pumping of independent compartments may be accomplished by the manipulation of the valves disposed between the chest 42 and any of the compartments to be pumped, with all other valves closed. A discharge outlet 49 leading from the pump terminates at a greater height than that to which the discharge end 50 is to be submerged, thus maintaining a free pumping discharge outlet at all times.

To further stiffen the carrier, hog rods 51, 52 and 53 and 54 connect the A frame with the ends of the carrier, the same may be made of wrought or bar stock, thus maintaining the same of a substantially even length during the life of the carrier; thus eliminating the necessity for check-ups of various kinds, whereas turn buckles are very essential in the line 16 because of the stretch disposed therein. To facilitate towing operations and the attachment of the carrier to a tug or other towing unit, straps 55 and 56 are disposed at either end of the carrier and at oppositely disposed sides terminating in eye connections 57 and 58 to which bridle elements 59 and 60 are attached.

The expeditious handling of long length logs can only be obtained through an overhead head equipment and the shifting of the carriage to the right position for lifting logs in an expeditious manner is very essential in the economical loading of logs.

In equipment of this kind it is highly essential that the same have relatively light draft because the same must be adapted for use in small arms of the sea where relatively light shallow channel depths lead therefrom.

to the open sea and the carrier must be seaworthy to permit the safe delivery of the cargo from such position to the central point of manufacture or place of use of the logs. 25 As logs become more valuable as our forests become denuded, the safe delivery of the logs is very essential and in carriers of this kind where tree length logs are to be used, I have found the structure as herein outlined is admirably adapted for this purpose. To aid in the rapid, partial submerging of the hull of timber construction and to increase the seaworthiness of the carrier, ballast is sometimes placed at the bottom of the hull. 30 While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

25 1. In a device of the class described, the combination of a flat bottomed submersible hull composed of a plurality of compartments at its ends, said compartments divided into sub-compartments, and an open hold disposed therebetween, means for flooding selected sub-compartments and/or the hold with water to cause a list of the carrier to the side selected, means for emptying any one of the flooded sub-compartments and/or 30 the hold, and means for rolling logs from outside the hold into the hold from a central power station disposed within the carrier.

2. A log carrier comprising a hull having an open hold disposed centrally therein and comprising a major portion of the hull having side walls and a central keelson running the full length and structural metal protectors extending in spaced relationship over and down each side wall, a plurality of water tight compartments disposed at each end of the hull, said compartments comprising a plurality of sub-compartments disposed in horizontal and vertical series, each being adapted to being flooded independent 45 of the other or all may be flooded at one time.

3. A carrier of the class described comprising a hull having its major portion of an open hold, a plurality of water tight compartments disposed at the fore and aft parts of the hull, said compartments comprising four in number, two being disposed at each end of the hull, one compartment disposed above the other and divided by a tween deck, each one of said compartments being divided into two sub-compartments, making all told eight chambers, four on each end of the hull, said sub-compartments adapted to being independently flooded thereby permitting unusual maneuverability and main-

taining buoyancy of the carrier at all times.

4. A log carrier comprising a flat bottomed hull having an open hold disposed therein, a plurality of water tight compartments disposed at the fore and aft parts of the hull, said compartments being arranged two in a vertically disposed series with a tween deck disposed between each series, said compartments being divided into sub-compartments arranged two in a horizontally disposed series, each sub-compartment being air and water tight, and means for flooding and/or emptying each compartment independent of the other to port or starboard, or perform any other maneuver necessary for the easy loading and unloading of logs.
